UNITED STATES PATENT OFFICE.

CHARLES E. POTTER, OF ST. LOUIS, MISSOURI.

COMBINED ALARM AND SIGNAL FOR DRY-PIPE SPRINKLER SYSTEMS.

1,182,206.

Specification of Letters Patent.

Patented May 9, 1916.

Application filed January 30, 1915. Serial No. 5,232.

To all whom it may concern:

Be it known that I, CHARLES E. POTTER, a citizen of the United States, residing at the city of St. Louis, State of Missouri, have invented a certain new and useful Improvement in Combined Alarms and Signals for Dry-Pipe Sprinkler Systems, of which the following is a full, clear, and exact description, such as will enable others skilled in the art to which it appertains to make and use the same, reference being had to the accompanying drawings, forming part of this specification, in which—

Figure 1 is a diagrammatic view showing a device embodying my invention applied for use in connection with a sprinkler system. Fig. 2 is a side elevational view of the combined alarm and signal with the housing which incloses the same in vertical section. Fig. 3 is an enlarged vertical section taken through the center of the device with parts thereof broken away. Fig. 4 is a detail elevational view of certain of the gears and pinions forming a part of the train of gearing or spring-actuated clock-work made use of in my improved device. Fig. 5 is a detail elevational view of a stop lever forming a part of the operating mechanism of my improved device and also showing certain parts of the mechanism which cooperates with said stop lever. Fig. 6 is a detail elevational view of a torsional spring which is utilized for moving one of the levers forming a part of the actuating mechanism of the device.

My invention relates generally to automatic sprinkler and fire alarm systems, and more particularly to a device which will automatically transmit to a central station an alarm and signal whenever the equilibrium of the fluid pressure within the pipes of the system is disturbed by the opening of one or more of the sprinkler heads resulting from fire or accident and which action necessarily results in a lowering of the pressure in the system.

The particular form of device herein illustrated and described is particularly intended for use in connection with what is commonly known as "dry pipe" sprinkler systems, that is, systems wherein all of the distributing pipes above the check valve in the riser are normally without water and therefore dry.

The principal object of my invention is to provide a comparatively simple inex-

pensive apparatus which may be conveniently and advantageously connected to one of the main supply pipes of the system and which device will, in the event of the opening of one or more adjacent sprinkler heads, transmit to the central station one or more signals which, in addition to giving the alarm, shows the approximate location of the open sprinkler head.

A further object of my invention is to provide a device of the character described with means for automatically transmitting to the central station a signal to show that the spring of the clock work or motor forming a part of the device is fully wound and that the device is properly set for use.

A further object of my invention is to provide certain details or features of improvement which will tend to increase the general efficiency and serviceability of an automatically released alarm and signal of the type to which my invention relates.

With the foregoing and other objects in view, my invention consists in certain novel features of construction and arrangement of parts, hereinafter more fully described and claimed.

Referring by numerals to the accompanying drawings, 10 designates one of the risers of a sprinkler system, 11 one of the lateral distributing pipes, the same carrying the usual automatic sprinkler heads such as 12. Located in the riser is an ordinary gate valve 13 and immediately above the same is a double check valve 14 having an intermediate or neutral chamber 15. Tapped into the housing of the double check valve and leading from the intermediate or neutral chamber therein is a short tubular connection 16, the outer end thereof being connected to the base of my improved signal and alarm device. This base is preferably in the form of a plate 17 provided in its upper portion with a chamber 18 and positioned on said plate and over said chamber is a diaphragm 19, preferably of thin resilient metal.

Fixed on top of plate 17 and overlying the edges of the diaphragm is a top plate 20 provided in its underside with a chamber 21 and positioned on top of the central portion of the diaphragm is a vertically disposed pin 22 which extends through an opening formed in the center of plate 20. Positioned upon this pin between the dia-

phragm and plate 20 is a compression spring 23, the same normally exerting downward pressure on the diaphragm.

Projecting upwardly from pin 22 is a small pin 24, the same being preferably threaded and carrying one or more nuts 24^a. Fixed to plate 20 is a pair of vertically disposed plates 25, the same being framed together in any suitable manner and these plates form a supporting frame for the shafts, gearing and operating parts of my improved device.

Journalized in the lower portions of the plates 25 and near one side thereof is a shaft 26 to which is fixed the inner end of a clock spring 27, the outer end thereof being fixed to one of the cross pieces which unite the plates 25. Fixed on shaft 26 is a gear wheel 28 and also a small disk 29, the latter is provided with a single tooth 30. One end of shaft 26 projects beyond the corresponding one of the plates 25 and said projecting end is made square or non-circular in order to receive a winding key. Gear wheel 28 meshes with a pinion 31, the same being loosely mounted on a shaft 32 which is journalized in plates 25, and said shaft carrying a large gear wheel 33 and a disk 34, the latter being provided in its edge with a notch 35. Fixed to the loosely mounted shaft 31 is a ratchet wheel 36 having a single tooth or shoulder, the same being engaged by the point of a spring-pressed pawl 37 which is pivotally mounted on gear wheel 33. Gear wheel 33 meshes with a pinion 38 which is fixed on a shaft 39, the same being journalized in plates 25. This shaft carries a gear wheel 40 which meshes with a pinion 41, the same being fixed on a shaft 42 which is journalized in plates 25. Fixed on this shaft 42 is a gear wheel 43 which meshes with a pinion 44, the same being fixed on a shaft 45 which is journalized in plates 25. This last mentioned shaft carries a cross plate 46 and a disk 47, which latter is provided with a single tooth or shoulder.

Fulcrumed on a stud 48 which is fixed to one of the plates 25 is a vertically disposed arm 49, the upper end of which is provided with a laterally projecting finger 50 which is adapted to engage behind the tooth or shoulder on disks 47.

Journalized on a stud 51 which is seated in one of the plates 25 is an eccentric disk 52, the same being provided with an eccentric slot 53 through which passes a pin 54, the same being carried by the lower end of arm 49. The edge of disk 52 is provided with a concentric portion *a*, and with an eccentric portion *b*. Formed in the edge of disk 52 between the concentric and eccentric edges are two notches 55, the same being spaced a slight distance apart and being adapted to receive the tooth 30 of disk 29. Journaled in plates 25 is a shaft 56 and positioned

thereupon is a torsional spring 57, one end of which is fixed to said shaft and the opposite end being fixed to one of the plates 25. Fixed on this shaft is a vertically disposed arm 58, the lower end of which is bent laterally to form a horizontally disposed finger 59, which engages the threaded pin 24 above the nuts 24^a thereon. The upper end of this arm 58 is adapted to engage either end of the cross plate 46, thus acting as a stop to hold the train of gearing against movement.

Spring 57 acts upon shaft 58 so as to normally hold the finger 59 down against the upper one of nuts 24^a, and consequently exerting pressure to move the upper end of arm 58 inwardly toward the cross plate 46. Carried by arm 58 above the shaft 56 is a transversely disposed pin 60, the same being adapted to engage the periphery of disk 34 and to occupy notch 35 therein.

Fixed on shaft 56 is an inwardly projecting arm 61 carrying a pin 62, the same being adapted to engage the concentric and eccentric edges of disk 52. The end of shaft 32 is extended a short distance beyond the front one of plates 25 and fixed thereon and insulated therefrom is a disk 63, the same being provided with a series of teeth 64 which are arranged in groups 95 so as to be instrumental in sending a predetermined signal over the circuit in which the device is located, which signal is registered at a central station. In the present instance I have shown this disk provided with teeth arranged in three groups of two each and thus this box or station would be known as No. 222 and when in operation will send in a corresponding signal.

Fixed on the front one of plates 25 adjacent to shaft 32 is a bracket 65 in which is positioned a set screw 66 and fixed to and insulated from this bracket is a flat spring 67, the free end of which occupies a position beneath the screw 66 and said free end being bent at right angles to form a contact finger 68. Fixed to spring 67 is a contact plate 69 and fixed thereto is a flat spring 70, the free end of which occupies a position adjacent to the free end of spring 67 and the end of said spring 70 being bent at right angles to form a contact finger 71 which occupies a position immediately adjacent to contact finger 68. Fixed to contact plate 69 and spring 70 and insulated therefrom is a contact plate 72, the same being provided with a contact point 73 which normally engages the free end of spring 70.

Suitable electric connections 74 lead from the contact plates 69 and 72 to a suitable indicator and recorder 75 located at a central station and this circuit is provided with a suitable battery 76.

The operation of my improved device is as follows: It will be understood that un-

tions and the teeth 64 of disk 63 will engage contact fingers 71 and 68, thereby sending in repeated signals to the central station, which will indicate the opening of one or more heads in the system. When disk 29 has completed its movement, tooth 30 will engage in the lower one of notches 55, thereby imparting movement to disk 52 and the pin 54 carried by the lower end of arm 49 will move into the angular portion of slot 53, thereby swinging the lower end of said arm outward and its upper end inward, thus bringing finger 50 into the path of travel of the shoulder on disk 47 and this action stops 15 the train of gearing from further movement.

The circuit in which the device and the indicator at the central station are located is normally closed, and as the teeth 64 pass the contact points 71 and 68 the circuit is first 20 broken by the engagement of the first tooth with finger 71, thereby raising spring 70 from contact point 73. Immediately after the tooth passes finger 71 the latter drops behind the tooth, thereby restoring contact 25 between spring 70 and contact point 73, thus momentarily closing the circuit. Immediately after this action takes place the tooth engages contact finger 68, thereby raising the free end of spring 67 and moving same 30 into engagement with screw 66 carried by plate 65, thus momentarily grounding the circuit. After the tooth passes contact finger 68 spring 67 returns to normal position and for an instant the circuit is closed. 35 These actions, namely, the breaking, the closing and grounding of the circuit, are repeated for each tooth carried by the disk 63 and by the reason of the fact that the teeth are arranged in groups a corresponding series 40 of repeated signals in the shapes of dots and dashes will be recorded by the register and indicated at the central station.

It will be understood that the operating parts of the device are inclosed in a suitable 45 housing, the same being positioned on plate 20 as shown in Figs. 1 and 2.

A device of my improved construction is comparatively simple, is wholly automatic in operation, transmits to the central station 50 a signal to show that the operating spring is properly wound and that the device is set for use, and likewise transmits to the central station repeated signals to show that one or more of the sprinkler heads of the 55 system which is controlled by the device are open.

It will be readily understood that minor changes in the size, form and construction of the various parts of my improved device 60 may be made and substituted for those herein shown and described, without departing from the spirit of my invention, the scope of which is set forth in the appended claims.

I claim:

65 1. The combination with a sprinkler sys-

tem and an electric circuit including an indicator, of a chamber in communication with the system, a spring-held diaphragm in said chamber, which diaphragm is adapted to be acted upon by the pressure of the water in 70 the system when one or more of the heads in said system are opened, a normally wound clock-work, a spring held member for normally holding the clock-work against movement, which member is acted upon by the 75 diaphragm when the latter is actuated by the pressure of the water in the system, and means coöperating with and adapted to be automatically actuated by the clock-work when the apparatus is set for use for transmitting a signal through the circuit. 80

2. The combination with a sprinkler system and an electric circuit including an indicator, of a chamber in communication with the system, a spring-held diaphragm in said chamber, which diaphragm is adapted to be acted upon by the pressure of the water in the system when one or more of the heads in the system are opened, a normally wound clock-work, a spring-held member for normally holding the clock-work against movement, which member is acted upon by the diaphragm when the latter is actuated by the pressure of the water in the system, means adapted to be operated by the clock-work for transmitting a series of repeated signals through the circuit, and automatically operating means coöperating with the clock work for actuating the transmitting means to transmit through the circuit a single signal when the spring which actuates the clock-work has been completely wound and the device is set for use. 95

3. The combination with a sprinkler system and an electric circuit including an indicator, of a spring-held diaphragm adapted to be acted upon by the pressure of the water in the system when one or more of the heads in said system are opened, a train of spring-driven gearing, means adapted to be 100 operated thereby for transmitting signals through the system, automatically operating means coöperating with the spring-driven gearing for actuating the signal producing means to transmit a single warning 105 signal through the circuit when the apparatus is set for use, and a spring-held member normally engaging a portion of the gearing to hold the same against movement, which member is adapted to be actuated by 110 the diaphragm when the same is subjected to pressure of the water in the system. 115

4. The combination with a sprinkler system and an electric circuit including an indicator, of a spring-held diaphragm adapted to be acted upon by the pressure of the water in the system when one or more of the heads in said system are opened, a train of spring-driven gearing, means adapted to be 125 operated thereby for transmitting signals 120 130 135 140 145 150 155 160 165 170 175 180

der normal conditions that portion of the riser 10 above the upper one of check valves 14 and the distributing pipes 11 leading from said riser are filled with air under 5 pressure and this air is prevented from escaping from the pipes by the upper one of the check valves. The neutral chamber 15 within the valve housing is normally filled with air, the same being under a certain degree 10 of pressure from the water in that portion of the supply pipe and riser below the lower one of check valves 14, but the pressure of this air is insufficient to move diaphragm 18 upwardly against the resistance offered by coil spring 23, and consequently 15 pins 22 and 24 are normally held at their lower limit of movement with finger 59 of arm 58 bearing on top of the upper one of nuts 24 (said arm being under control of 20 spring 57) and when so positioned the upper end of arm 58 engages one end of cross plate 46, thereby acting as a stop and holding the train of gearing against movement.

Under normal conditions the various 25 parts of the operating mechanism occupy the positions seen in Fig. 3.

It will be understood that in devices of this character it is desirable and essential that the central station be notified that the 30 spring is wound and that the device is in condition for proper operation and to this end I have provided means for automatically transmitting a single signal to the central station when the spring has been 35 completely wound.

Spring 27 is wound by the application of a key to the projecting end of shaft 26 and when the winding movement has been completed disks 29 and 52 occupy the positions 40 illustrated in Fig. 5 with the pin 52 of arm 49 occupying the lower end of the concentric portion of slot 52, thereby holding finger 50 out of engagement with the shoulder on disk 47, and pin 62 on arm 61 occupies a 45 position on the high concentric edge of disk 52, thereby rocking shaft 56 so that the upper end thereof is moved out of engagement with the cross plate 46 and pin 60 is withdrawn from notch 35. When so positioned 50 there is nothing to hold the train of gearing against operation resulting from the power stored in spring 27 and as said power acts, shaft 26 and gear wheel 28 are moved anti-clock-wise and this movement is transmitted 55 to the various members forming the train of gearing, the shafts on which said members are mounted, and the parts carried thereby. As shaft 26 is operated by the power stored in the completely wound 60 spring, tooth 30 on disk 29 will engage in the immediately adjacent notch 55, thereby imparting movement to disk 52 and simultaneously gear wheel 28 drives pinion 31, shaft 32 and disk 34. These last mentioned 65 parts make a complete revolution during

which time the disk 52 is moving a comparatively short distance, this difference in movement being due to the relative sizes of gear wheel 28 and pinion 31. At the beginning of the movement the parts are in 70 the positions seen in Fig. 5 and after the disk 52 has moved a comparatively short distance pin 62 will ride off the high concentric portion *a* of disk 52 onto the lower eccentric portion *b*, thereby permitting shaft 75 56 to rock slightly and which rocking movement occurs when disk 34 has made a complete revolution so that pin 60 drops into notch 35. The torsional spring 57 is effective in bringing about the movement of arm 80 58 and as soon as this movement takes place the upper end of said arm moves into the path of travel of the cross plate 46, and one end of the latter is engaged to stop and hold the train of gearing against further movement.

Shaft 32 which carries pinion 31 makes a complete revolution as just described, and the teeth 64 on disk 63 pass the contact fingers 71 and 68 of springs 70 and 67, thereby 90 sending in to the central station a single signal to indicate that the device is properly wound and set for use. After this single signal has been transmitted through the circuit to the central station the various operating parts of the device occupy the positions illustrated in Fig. 3. In the event that one or more of the sprinkler heads in that section of the system in which my improved device is located open by reason of heat from 95 an adjacent fire or through accident the release of air through the opened head or heads naturally lowers the pressure in the distributing pipes 11 and riser 10 above the upper one of check valves 14, thereby permitting 100 water in the riser and supply pipe below the check valves to rush upwardly through the neutral chamber 15 and upwardly through riser and its distributing pipes, and which water will discharge from the open head or 105 heads. As soon as this flow of water takes place, connection 16 will be instantly filled with water and the pressure thereof will be directed against the underside of diaphragm 110 18, thereby raising the same and overcoming the resistance offered by spring 23. Following this action pin 23 carrying 115 nuts 24 will be moved upward, thereby engaging finger 59 on the lower end of arm 58 and swinging the latter so that its 120 upper end is moved outward away from the cross plate 46. This releases the train of gearing and the same immediately starts to operate under the power stored in spring 27 and disk 29 carried by shaft 26 will make 125 practically a complete revolution during a portion of which, the edge of said disk bears against that portion of the disk 52 between the notches 57. Gear wheel 28 drives pinion 31, causing the same to make several revolu- 130

through the system, a spring-held member normally engaging a portion of the gearing to hold the same against movement, which member is adapted to be actuated by the diaphragm 5 when the same is subjected to pressure of the water in the system, and automatically operating means coöperating with the spring driven gearing for releasing the holding member to permit the gearing and 10 the transmitting means to operate and transmit a single signal through the circuit when the driving spring of the gearing is wound and the device set for operation.

5. In an apparatus of the class described, 15 a normally wound clock-work, means adapted to be actuated thereby for producing signals in an electric circuit, means arranged to operate automatically when the device is set for use for effecting an operation of 20 the signal transmitting means to transmit a single signal, a spring-held member for normally holding the clock-work against operation, a member adapted to be operated by the pressure of the water 25 in the system with which the device is associated, and connections between said last mentioned member and the clock work holding member.

6. In an apparatus of the class described, 30 a normally wound clock-work, means adapted to be actuated thereby for producing signals in an electric circuit, a spring-held member for normally holding the clock-work against operation, a member adapted 35 to be operated by the pressure of the water in the system with which the device is associated, connections between said last mentioned member and the clock work holding member, and means for automatically effect- 40 ing a release of the clock-work holding

means to permit the same to operate for a predetermined period of time immediately after the spring of said clock-work has been completely wound.

7. The combination with a sprinkler system and a circuit provided with an indicator, of a spring-driven signaling device co-operating with the circuit, means adapted to be actuated by the pressure of the water in the system when one or more of the heads 45 in said system are opened for normally holding the spring-driven means against operation, and automatically operating means adapted to release the holding means to permit a partial operation of the signaling 50 means at the time the apparatus is properly set for use.

8. The combination with a sprinkler system and a circuit provided with an indicator, of a housing, the chamber within which 60 is in communication with the sprinkler system, a spring-held diaphragm within said housing, a spring-driven signaling device co-operating with the circuit, a spring-held member adapted to be actuated by the dia- 65 phragm, which member normally engages a portion of the signaling device to hold it against operation, and automatically operating means adapted to release the holding means to permit a partial operation of the 70 signaling means at the time the apparatus is properly set for use.

In testimony whereof I hereunto affix my signature in the presence of two witnesses, this 28th day of January, 1915.

CHARLES E. POTTER.
